UNITED STATES PATENT OFFICE.

ALBERT TEICHMANN, OF ZEITZ, GERMANY.

METHOD OF RECOVERING GRAPHITE FROM WORN-OUT CRUCIBLES.

1,080,085.

Specification of Letters Patent.

Patented Dec. 2. 1913.

No Drawing.

Application filed November 5, 1912. Serial No. 729,642.

To all whom it may concern:

Be it known that I, ALBERT TEICHMANN, a subject of the Emperor of Germany, and a resident of Zeitz, in Saxony, Germany, have 5 invented a new and useful Improvement in Methods of Recovering the Graphite from Worn-Out Crucibles, of which the following is a specification.

The valuable graphite contained in worn 10 out broken crucibles has up to now gone to waste, because no practical and economical process to recover it was known. This useful effect may now be attained by the method which forms the subject matter of 15 the present invention and is carried out as follows: The worn out crucibles are broken into pieces having the size of, perhaps, a fist, and these pieces are subjected for from four to twelve hours, to the action of sulfuric, muriatic or nitric acid, or any other equivalent acid as may be best suited to the composition of matter of which the respective crucibles were made, the object of this treatment being to break the union between 20 the graphite, which is one of the components of that composition of matter and the other components of the same. The thus treated pieces are heated to red heat in a suitable furnace, kiln, retort, or the like, in 25 order to evaporate the acid and to render the pieces rather brittle and friable. Thereafter the pieces are passed between the rollers of a crushing mill for the purpose of 30 loosening the slack, which then is separated 35 from the crushed pieces by a sieve or the like. It will be understood that where the word "slack" is used in this specification and in the claims comprised herein, that I means to include in said word substances or- 40 dinarily used in the manufacture of graphite crucibles such as binding materials which are other than graphite. The remaining pieces are subjected repeatedly and for 45 as long a time as possible to the action of a grinding mill and the product obtained by each grinding operation is sieved, this procedure being carried through in such a manner that a plurality of sizes of grain and of 50 graphite dust, for instance six sizes of grain and two sorts of dust are obtained.

It is of great importance that the rollers of the grinding mill rotate with absolutely the same speed; even the very small difference which is brought about by one tooth

more or less of the cog wheels, or by unusual spaces between the teeth of the cog wheels impairs the quality of the product to a remarkable degree. It is therefore preferable either to employ cog wheels of exactly the same number of teeth, or to impart power only to one of the rollers and to let this roller rotate the other one merely by the friction produced by the grinding action.

What I claim as new and desire to secure 65 by Letters Patent is:

1. The method of recovering the graphite from worn out, broken crucibles, consisting in subjecting the crucible pieces to the action of an acid adapted to loosen the union 70 between the graphite in said pieces and the other component substances of the same; heating the thus treated pieces to a glowing temperature; crushing them so as to loosen the slack; separating the slack from the 75 crushed pieces; and grinding the latter.

2. The method of recovering the graphite from worn out broken crucibles, consisting in subjecting the crucible pieces to the action of sulfuric acid; heating the thus treated 80 pieces to a glowing temperature; crushing them so as to loosen the slack; separating the slack from the crushed pieces; and grinding the latter.

3. The method of recovering the graphite 85 from worn out broken crucibles consisting in subjecting the crucible pieces to the action of a mineral acid, heating the thus treated pieces to a glowing temperature, crushing them so as to loosen the slack, separating the slack from the crushed pieces and 90 grinding the latter.

4. The method of recovering the graphite from worn out broken crucibles, consisting in subjecting the crucible pieces to the action of a mineral acid for a number of hours, 95 heating the thus treated pieces to red heat, crushing them so as to loosen the slack, separating the slack from the crushed pieces, grinding the latter, and separating the 100 product of the grinding process into grains and dust.

In testimony whereof I affix my signature in presence of two witnesses.

ALBERT TEICHMANN.

Witnesses:

WOLDEMAR HAUPT,
HENRY HASPER.
